(57) **CLAIM**

The ornamental design of a near-infrared spectroscopy (NIRS) sensor assembly, as shown and described.

DESCRIPTION

FIG. 1 is a top side perspective view of a NIRS sensor assembly;

FIG. 2 is a bottom side perspective view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line representations in the figures are for the purpose of illustration only and form no part of the claimed invention.
